Primary Examiner — Eric Goodman*Assistant Examiner* — Amy Wierenga*(74) Attorney, Agent, or Firm* — Cantor Colburn LLP(57) **CLAIM**

I claim, the ornamental design for a toner cartridge for copy machine, as shown and described.

DESCRIPTION

FIG. 1 is a front perspective view of a toner cartridge for copy machine showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of the encircled portion 8 in FIG. 1.

The broken lines illustrating portions of the toner cartridge for copy machine are for environmental purpose only and form no part of the claimed design. The shade lines in the figures show contour and not surface ornamentation. The dot dash lines encircle portions of the claimed design that are illustrated in different magnifications and form no part of the claimed design.
